UNITED STATES PATENT OFFICE.

ALBERT D. CAYWOOD, OF CHICAGO, ILLINOIS.

FIRE DOOR AND WALL.

No. 918,824.

Specification of Letters Patent.

Patented April 20, 1908.

Application filed December 11, 1908. Serial No. 466,957.

To all whom it may concern:

Be it known that I, ALBERT D. CAYWOOD, a citizen of the United States, residing at Chicago, in the county of Cook and State of Illinois, have invented a new and useful Improvement in Fire Doors and Walls, of which the following is a specification.

My invention relates particularly to a fire-proof construction adapted for doors and walls; and my primary object is to provide a construction of the character indicated which can be manufactured at a moderate cost, which has excellent heat-resisting qualities, and which is strong and durable and of slight appearance.

The accompanying drawings illustrate the invention embodied in a fire door, but it will be understood that the invention is adapted to wall and ceiling construction.

In the accompanying drawings—Figure 1 represents a perspective view of a fire door constructed in accordance with my invention; Fig. 2, a broken perspective view of the same on a larger scale and showing marginal connecting members employed for connecting the edge plates of the door with the structure of the door-body; Fig. 3, a broken transverse sectional view taken as indicated at line 3 of Fig. 4; Fig. 4, a broken sectional view taken as indicated at line 4 of Fig. 3; Fig. 5, a broken perspective view showing the preferred manner of connecting the flanged metallic plates employed in the construction at points removed from the edges of the door; Fig. 6, a perspective view of the connecting member shown in Figs. 3, 4 and 5; Fig. 7, a perspective view of an edge-plate connecting-member employed; Fig. 8, a perspective view of a corner connecting-member employed; Fig. 9, a broken perspective view showing a modified means for connecting the edge-plates of the door with the structure of the door-body; Fig. 10, a broken perspective view showing the structure without edge-plates and with the air-spaces filled with a heat-resisting or refractory material, such as fire-clay or cement; and Fig. 11, a broken sectional view showing a modified form of flanged plate and connecting clip.

Referring to Figs. 1 to 8 inclusive, the door illustrated comprises a series of parallel flanged metallic plates A extending vertically; a series of flanged metallic plates A¹ extending transversely, or horizontally; a series of intermediate clips A² connecting the flanges of the plates A and A¹; a series of

edge connecting members A³ (one shown); corner-connecting members A⁴; and peripheral channel-bars A⁵ and edge-bars A⁶ connected with the members A³ and A⁴, by means of screws A⁷. Each of the flanged plates A comprises a sheet metal plate having at its lateral portions oblique flanges 1 and 2 which extend at an acute angle to the body of the plate and carry, respectively, out-turned flanges 3 and 4. The flanges 1 and 3 are preferably somewhat larger than the flanges 2 and 4, so that the flanges may interlock in the manner shown in Figs. 3 and 5, while the bodies of the plates lie flush with each other. The plates A¹ are provided with similar flanges, which are similarly numbered. The flanges 1 and 3 considered together may be regarded as a V-shaped flange having an out-turned member; and the flanges 2 and 4 considered together may be regarded as a V-shaped flange having an out-turned member, the out-turned members overlapping when the plates are ranged edge to edge, as will be readily understood from Fig. 5. When so ranged, the adjacent flanges of two adjacent plates afford a dove-tail projection. Each clip or connecting member A² has a pair of flanges 5 and 6 which converge so as to form between them a dove-tail groove adapted to receive the dove-tail projections of the plates A; and at substantially right-angles thereto, a pair of flanges 7 and 8 which converge to form a dove-tail groove adapted to receive the dove-tail projections of the cross-plates. Thus, it will be understood that the members A² may be slipped on to the flanges of the plates A to connect them, after which the flanges of the plates A¹ may be slipped through the free flanges of the members A². Thus, the bodies of the plates A will be separated from the bodies of the plates A¹ by spaces 9, which may serve either as air-spaces or as spaces for receiving refractory material according to the illustration given in Fig. 10. The clips or guide-members A² may be employed at alternate intersections of the flanges of the plates, as will be understood from Fig. 4. Each connecting member A³ preferably comprises a pair of guide-members 10 and 11 carried by a shank 12 which extends toward the edge of the door and is equipped with a perforate internally-threaded lug 13 adapted to receive the corresponding screw A⁷. Each of the guide-members 10 and 11 is provided with a vertical channel adapted to receive

the flanges of the vertical plates A, and with a cross-channel adapted to receive the flanges of the cross-plates A¹. The web of the channel-bar A⁵ and the edge-plate A⁶ are 5 provided with perforations 14 through which the screws A⁷ extend. Each corner-connecting member A⁴ preferably comprises a guide-member 15 and a shank 16 having arms 17 and 18 equipped with perforate 10 threaded lugs 19 adapted to receive the screws A⁷ located at the corners of the door. The guide-members 15 are equipped with a vertical channel adapted to receive the flanges of the vertical plates A and with a 15 cross-channel adapted to receive the flanges of the marginal cross-plates A¹.

It will be understood from the foregoing that the guide-members or slides which serve to connect the flanges of the plates and also 20 to attach the edge-members of the door are confined between the vertical plates and cross-plates, so that the exposed surfaces of the door are practically smooth and present no objectionable projections. The connecting members are thus securely housed and 25 protected from injury which might result either from blows or from heat, in case of fire.

In the modification illustrated in Fig. 9, the same flanged vertical plates A and 30 flanged cross-plates A¹ are employed; and the same interior connecting members A² are employed. A different method of connecting the edge-plates of the door is employed, however. According to this modification, 35 the plates A and A¹ are provided at the margins of the door with guide-members 20; and channel-bar edge-members A⁸, equipped with guides 21 adapted to engage the guides 20, are employed as binding members. The 40 guide members 20 may be formed by partially severing a portion of the metal of the plate and stamping it into angle form to form the guide. The guides 21 are formed to interlock with and inclose the guide-members 20.

45 In the modification illustrated in Fig. 10, the door structure is the same as the constructions previously described, except that the spaces 9 between the plates are filled with a refractory or non-conducting material 50 22. Any suitable material may be used for the purpose, such, for instance, as asbestos, fire-clay or cement.

55 In the modification shown in Fig. 11, the construction is similar to the constructions previously described, except that the flanges of the metal strips or plates are somewhat differently formed, and the connecting clips are slightly changed to conform to the change in the flanges. This construction comprises 60 vertical plates A⁹; cross-plates A¹⁰ and connecting members A¹¹. The plates or metal strips are provided with inturned flanges 23 which are at right angles to the bodies of the plates, and which, in turn, carry inturned 65 flanges 24 lying in a plane parallel with the

plane of the bodies of the plates. The plates are placed side by side with adjacent flanges 23 in contact with each other and adjacent flanges 24 turned away from each other. Thus, the adjacent flanges of two plates virtually form a T-flange; and the arms or members of the clips A¹¹ are bent to afford T-slots which engage said T-flanges, it being understood that each member A¹¹ has a vertical T-slot and a transverse T-slot, whereby 70 the flanges of the cross-strips will be connected with the flanges of the vertical strips at the points of intersection.

In each of the described constructions, the metal strips are joined together by internal 80 devices contained in the spaces between the vertical strips and the cross-strips, and the door presents practically plane lateral surfaces at the exterior.

Hinges may be connected with the door 85 in any suitable manner, if desired. No hinges are shown, but it may be remarked that the edge-plates A⁶ are sufficiently strong for connection with butt hinges. If desired, the door may, of course, be employed 90 as a sliding door.

It is obvious that the construction disclosed is adapted not only to door construction but to wall construction generally, such as partitions, ceilings, etc. It is noteworthy 95 that the flanges of the metal strips serve to lend rigidity and strength to the strips; and the crosswise relation of the two series of strips serves to contribute to the door, in a remarkable degree, the qualities of rigidity, 100 strength and durability.

The foregoing detailed description has been given for clearness of understanding only, and no undue limitation should be understood therefrom.

What I regard as new and desire to secure by Letters Patent, is—

1. In a construction of the character set forth, the combination of a series of plates extending in one direction and equipped with 110 adjacent flanges, a series of plates extending crosswise with relation to the first-named plates and equipped with adjacent flanges, the flanges of the second-named series of plates being turned toward the flanges of the 115 first-named series of plates, and internal connecting members.

2. In a construction of the character set forth, the combination of two series of flanged metal plates arranged in crosswise 120 relation with the flanges of the two series turned toward each other, and means connecting the flanges of each series of plates together.

3. In a construction of the character set 125 forth, the combination of two series of flanged metal plates arranged in crosswise relation with the flanges of the two series turned toward each other, and means connecting the flanges of each series of plates 130

- together and to the flanges of the other series of plates.
4. In a construction of the character set forth, the combination of two series of flanged metal plates arranged in crosswise relation, the flanges of the two series being turned toward each other so as to space the bodies of the plates, and internal connecting members joining the plates together.
- 10 5. In a construction of the character set forth, the combination of two series of flanged plates arranged in crosswise relation, the flanges of the two series of plates lying adjacent to and crossing each other, and connecting members joining said flanges, each connecting member having flange-receiving channels crossing each other.
6. In a construction of the character set forth, the combination of two series of flanged metal plates arranged in a crosswise relation with flanges adjacent to each other, and connecting members at intersections of said flanges, each connecting member having a pair of flange-receiving channels crossing each other.
7. In a construction of the character set forth, the combination of two series of flanged metal plates arranged in crosswise relation with the flanges turned toward each other and spacing the series of plates with relation to each other, said flanges being complementary, whereby the adjacent flanges of two adjacent plates afford a tenon, and connecting members joining said flanges, each connecting member having flange-receiving channels extending crosswise with relation to each other.
8. In a structure of the character set forth, the combination of two series of flanged plates arranged in crosswise relation with flanges lying adjacent to each other, internal connecting members joining said flanges, binding members for the structure, and edge connecting members connected with the flanges of said plates and with said binding members.
9. A structure of the character set forth, comprising two series of flanged plates arranged in crosswise relation with flanges adjacent to each other, binding plates for the structure, and connecting members, each having flange-receiving channels arranged in crosswise relation and having a member connected with one of said binding plates.
10. A structure of the character set forth, comprising two series of flanged plates with flanges turned toward and crossing each other, connecting members joined to certain of said flanges and extending to the edge portions of the structure, and channel-form binding plates embracing the marginal portions of the structure and joined to said connecting members.
11. A structure of the character set forth, comprising two series of flanged plates arranged in crosswise relation with flanges adjacent to and crossing each other, intermediate connecting members joining the flanges of said plates, corner connecting members each provided with flange-receiving channels extending crosswise with relation to each other and carrying members adapted for connection with two binding plates, and binding plates connected with said last-named members.
12. A structure of the character set forth, comprising two series of flanged metal plates arranged in crosswise relation and having their flanges turned toward each other, means rigidly connecting said plates together, and refractory material contained in the spaces between said plates.

ALBERT D. CAYWOOD.
